Patented Dec. 16, 1924.

Des. 66,245

UNITED STATES PATENT OFFICE.

LA VERN R. PARR, OF LOS ANGELES, CALIFORNIA.

DESIGN FOR A SIGNAL-LAMP FACEPLATE.

Application filed June 3, 1922. Serial No. 2,514. Term of patent 3½ years.

To all whom it may concern:

Be it known that I, LA VERN R. PARR, a citizen of the United States, residing at Los Angeles, in the county of Los Angeles and State of California, have invented a new, original, and ornamental Design for Signal Lamp Faceplate, of which the following is a specification, reference being

had to the accompanying drawing, forming part thereof.

The figure is a view in elevation of a signal lamp face plate, showing my new design.

I claim:

The ornamental design for a signal lamp face plate, as shown.

LA VERN R. PARR.
